WILLIAM B. SIMPSON, OF SHREVEPORT, LOUISIANA.

EXPLOSIVE-ENGINE.

1,126,713.

Specification of Letters Patent.

Patented Feb. 2, 1915.

Application filed June 17, 1913. Serial No. 774,224.

To all whom it may concern:

Be it known that I, HENRY THOMAS CREW, a citizen of the United States, residing at Shreveport, in Caddo parish, State of Louisiana, have invented a new and useful Explosion-Engine, of which the following is a specification.

This invention has reference to improvements in explosion engines of either the two or the four cycle type, and its object is to provide means whereby greater efficiency is obtained from the explosions than is the case with the ordinary type of explosion engines.

Ordinarily in an explosion engine of the two or four cycle type the explosion occurs so that the impulse is delivered to the piston at approximately the point of dead center and from this point to the ninety degree position of the crank shaft with respect to the dead center at which the impulse is delivered to the piston, the explosion chamber is expanding and the efficiency of the burning gases is rapidly diminishing, wherefore at the point where the impulse should be most efficient it has lost a large part of its force and the efficiency of the engine is materially lower than it should be with the energy represented by the explosion of the charge.

With the present invention this relatively inefficient arrangement is to a great extent eliminated for the impulse is delivered when the crank shaft is at substantially right angles to the line of reciprocation of the piston and consequently such impulses are delivered at the point of greatest leverage with respect to the crank shaft.

In accordance with the present invention two pistons are provided in the power cylinder, or in the event of more than one power cylinder, in each of said power cylinders, and these pistons are connected to the crank shaft in quarter phase relation, and in order to obtain the best results one piston is so connected to the crank shaft as to have a smaller extent of travel than the other, this being most readily accomplished by having the respective cranks of different lengths.

The invention will be most readily understood by a description of its application to a two cycle type of engine, and hence the invention will be described with reference to the two cycle type of engine without, however, limiting the invention to such type, for the invention may be adapted to a four cycle

type of engine by an appropriate change in the valve structure as is well understood by those familiar with explosion engine practice.

While the description of the invention is based upon a showing of a practical form of explosion engine, it will be understood that the invention is by no means limited to the construction illustrated in the drawings, but such construction may be changed and modified so long as such changes and modifications mark no material departure from the salient features of the invention.

In the drawings:—Figure 1 is a section at right angles to the longitudinal axis of the crank shaft of an engine embodying the present invention, the section being substantially diametric of the engine cylinder, some parts being shown in elevation. Fig. 2 is a section with some parts in elevation on a plane substantially at right angles to that of Fig. 1. Figs. 3, 4, 5 and 6 are elevations of the cylinder with parts broken away and in section showing different phases of operation of the piston. Fig. 7 is a perspective view of the crank shaft.

While double piston explosion engines wherein the pistons may reciprocate oppositely within a single cylinder and both act upon a single crank shaft, have heretofore been proposed, such pistons have been so connected up to the crank shaft as to reciprocate oppositely in one hundred and eighty degree relation one to the other, but in their relation to the crank shaft such oppositely reciprocating pistons do not differ from single reciprocating pistons and no provision is made for causing the explosive impulse to exert its greatest force when the crank shaft is in the most advantageous relation to the piston.

In many respects an engine embodying the present invention may be built in accordance with the customary explosion engine practice, and in the drawings there is shown a cylinder 1 and a crank shaft 2, which latter, however, differs from the common practice in having a crank 3 and other cranks 4 displaced circumferentially by about ninety degrees from the crank 3, wherefore the cranks may be described as dephased by ninety degrees or may be stated to be in quarter phase relation. Moreover, the cranks 4 are shorter than the crank 3, that is, they are of less radial extent from

the axis of the crank shaft, and this difference may be in the ratio of two to three although by no means limited to any such exact proportions, since the design of the 5 engine will control these proportions more or less.

The crank shaft is shown as provided with bearings 5 in a body member 6, which in the upright or marine-type of engine may 10 be utilized as a support for the entire engine. The body member 6 may follow the usual engine practice whether the engine is to operate on the two cycle or four cycle principle, and although the engine illustrated in the drawings operates on the two cycle principle the body member is not utilized as a receiving and compressing chamber for either air or the explosive mixture, but these features are not material to the present 15 invention and hence may be varied in accordance with the wishes of the builder. The crank shaft 2 carries fly wheels 7, usually two in number, although this feature is not material to the present invention.

25 The cylinder 1 is shown as provided with a water jacket 8 as is customary, and also with a fuel inlet duct 9 and an exhaust duct 10 located approximately opposite each other at a point nearly midway of the length 30 of the cylinder, although the exact location of these parts depends upon the proportions of the crank shaft and other factors. Within the cylinder there are two pistons 11, 12, respectively, which may be of the same 35 length, although this in itself is not material, and each piston has the end or head facing the other piston hollowed out, as indicated at 13, 14, respectively, so that the facing heads of the two pistons may be 40 brought into close relation with the hollowed out portions 13 and 14 together defining a chamber which, as will hereinafter appear, constitutes an explosion chamber. The piston 11 carries a deflector 15 between one 45 edge of the piston and the center of the chamber 13, this deflector being of a length to enter the chamber 14 for the greater portion of the depth thereof when the pistons 11 and 12 are at their closest approach. The 50 piston 11 is provided with a piston rod 16 extending through a packing gland 17 in the head 18 of the cylinder 1 remote from the base 6, and this piston rod outside the cylinder is fast to a cross head 19 moving in 55 guides 20 mounted on the head 18, the cross head being of greater length than the outside diameter of the cylinder 1 including the water jacket 8. The other piston 12 is connected by a pitman 21 with the crank 3, 60 while the cranks 4 are each connected by a pitman 22 to a corresponding end of the cross head 19.

The inlet duct or pipe 9 is connected to a carbureter 23 or other suitable means for the 65 supply of fuel and this carbureter is con-

nected by a pipe 24 to the interior of the cylinder 1 between the piston 11 and the head 18 and furthermore the pipe 24 is provided with an air inlet valve 25.

In the particular construction shown the 70 piston rod 16 is traversed longitudinally by a spark plug 26 having terminals 27 within the hollowed out portion 13 of the piston 11 and contacts 28, 29, one carried by the cross head 19 and the other by one of 75 the guides 20 serve as means for including the spark plug in a suitable circuit for the production of a spark at the terminals 27 at the proper time for the ignition of a compressed explosive charge within the cylinder. While the spark plug is shown in the drawings as carried by the piston rod 16, it will be understood that it may be otherwise located and the energization of the spark plug otherwise controlled, so as to cause the 80 ignition of the charge at the proper time. The particular construction or disposition of the spark plug does not form any part of this invention, and hence it is deemed unnecessary to describe the various ways in 85 which the spark plug may be arranged, the one shown being sufficient for an understanding of the operation of the invention.

If it be assumed that the parts are in the 90 position shown in Figs. 1 and 2 with a compressed charge as of explosive mixture within the chamber defined by the hollowed out portions 13 and 14, and that just before reaching this position the charge has been fired by the passing of a spark across the terminals 27, then by the time the parts 95 have assumed the position shown in Fig. 1 the charge has become fully ignited and the full force of the impulse is directed against both the pistons 11 and 12, but the piston 12 has its crank 3 on dead center. The piston 11, however, has its cranks 4 at the ninety degree position, so that the 100 full force of the explosion acts on the cranks 4 at the most advantageous position, or the 105 position of greatest leverage, and the effect of the explosion is transmitted to the crank shaft with an energy far in excess of that 110 which occurs from an explosion of like degree or power taking place in an ordinary single piston explosion engine where the piston is fully retracted and the full force of the explosion occurs, while the crank shaft is on dead center. The power stroke of the 115 engine of the present invention is that caused by the movement of the piston 11 toward the head 18, thus turning the crank shaft 2 counter-clockwise as viewed in Fig. 1. The 120 rotative movement of the crank shaft is, of course, imparted to the crank 3 and by way of the piston rod 21 to the piston 12, and this piston travels in a direction away from the head 18 and also away from the piston 11, the explosion acting on the piston 12 in 125 much the same manner as it does in the 130

ordinary explosion engine, so that the impulse acting on the crank shaft is similar to that of the ordinary explosion engine with the added impulse due to the full force of the explosion acting on the piston 11, and while the force of the explosion acts through the piston 11 with decreasing leverage as the cranks 4 approach the upper dead center, the action of the piston 12 is with increasing leverage upon the crank shaft 2, and, moreover, the piston 12 moves with greater speed than the piston 11 because of the greater length of the crank 3. As the piston 11 moves toward the head 18 the air within the chamber between the piston 11 and head 18 is compressed and forced through the pipe 24 and through the carbureter 23 and as soon as the duct 9 is uncovered by the movement of the piston 11 toward the head 18 the compressed air with the fuel taken up in the carbureter 23 is injected with force into the now enlarged chamber formed by the cavities 13 and 14 and the space between the corresponding heads of the pistons, the relative positions of the parts at the completion of the power stroke of the piston 11 being indicated in Fig. 3. While the inlet port at the inner end of the duct 9 was being uncovered by the movement of the piston 11 on its power stroke, the outlet port at the inner end of the duct 10 has also been uncovered. The deflector 15, however, tends to direct the incoming stream of fuel under pressure away from the exhaust pipe or duct 10 and toward the retreating piston 12, thus in the manner common in two cycle engines scavenging the burned gases from the interior of the cylinder and out through the exhaust duct 10. When the piston 11 has reached the full limit of the power stroke, thus uncovering the inlet and exhaust ports, the piston 12 has only moved a little more than half its full stroke or until the crank 3 has reached the ninety degree position from the upper dead center, all as shown in Fig. 3. On a further rotative movement of the crank shaft from the position shown in Fig. 3 to the position shown in Fig. 4, the piston 12 reaches its limit of movement away from the head 18 and the piston 11 has also traveled away from the head 18 for a little more than half its stroke, or with the cranks 4 at the ninety degree position from upper or lower dead center. The movement of the piston 11 away from the head 18 tends to create a vacuum within the space between the piston 11 and head 18 and atmospheric air is drawn in through the valve 25. Now on the next quarter revolution of the shaft 2 to the position shown in Fig. 5 the movement of the piston 11 has continued until the cranks 4 are at lower dead center, thus marking the limit of movement of the piston 11 away from the head 18. In the meantime, the piston 12 has moved toward the head 18 and also toward the piston 11, thus partially compressing the charge confined between the two pistons. Now, on a further rotative movement of the crank shaft the piston 12 continues its movement toward the head 18 and the piston 11 begins its movement toward the head 18. The piston 12, however, moves with greater rapidity than the piston 11 because of the greater length of the crank 3 and hence the piston 12 approaches the piston 11 and this approaching continues until the cranks have moved through an arc of about sixty-seven and one-half degrees, after which the piston 11 gradually draws away from the piston 12, until the crank 3 is on upper dead center. The position of greatest approach of the two pistons (see Fig. 6) is at a point within about twenty-two and one-half degrees of the position shown in Fig. 1 and at this position of greatest approach which is also the position of greatest compression of the charge, the parts may be so timed that contact is made at the contacts 28 and 29 in a manner to cause the passage of a spark between the terminals 27, wherefore the charge is ignited at the point of greatest compression and is thoroughly inflamed throughout, and hence imparts its impulse at the time the crank 3 has reached upper dead center, such position of the parts being shown in Fig. 1, and hence the full power stroke of the piston 11 begins under the most favorable conditions of leverage of the crank shaft 2. While there is a slight reduction of the compression after the passing of the spark and before the complete ignition of the charge, the loss thus caused is but a small fraction of the loss caused by the firing of the explosive mixture in a single piston engine or in a double piston engine where the crank must pass the dead center before the force of the explosion is at all active and must complete about one-half the power stroke before the crank is in the most effective position, but at which time the force of the explosion has been spent to a material extent without commensurate effect upon the crank shaft. The discharge of the burned or spent gases takes but one-quarter of a revolution of the crank shaft, thus reserving three-fourths of the revolution for the intake and assimilation of the fuel mixtures. This aids to a marked extent in the reduction of internal heat, wherefore less cooling agent is required to keep the engine cool than would otherwise be the case and the cooling problem is to a like extent simplified. Again, during the intake of fuel the piston 12 is moving rapidly away from the intake and hence tends to create vacuum conditions by somewhat enlarging the area of the chamber between the pistons and thus serves to retain all the fresh fuel

- instead of more or less of it escaping through the exhaust port because of the force with which the fuel enters the explosion chamber under the compression caused by the piston
- 5 11. The hollowed out matching ends of the pistons provide a compression and explosion chamber of suitable size, while at the same time permitting a very close approach of the pistons.
- 10 It is unnecessary to describe any means for governing the engine or to show a four cycle type of engine, since these features are readily understood by those familiar with explosion engine practice, for the principles 15 of the present invention are not confined to any single type of engine, but may be used with either of the prevailing types. Nor is the engine limited to the use of a crank shaft for the same relation of movement of the 20 pistons may be brought about with other forms of driving devices than crank shafts, it only being necessary that the pistons shall have movements related as described, that is, their movements shall be in quarter phase 25 relation or such approach thereto as shall produce results such as are accomplished by the quarter phase relation of movement herein set forth.

While the engine has been shown in the 30 drawings as an upright or marine type of engine, it will be understood that the same principles are applicable to a horizontal engine, or to a tandem engine of the explosion type, and hence the invention is not 35 limited to any particular type of engine to the exclusion of all others.

Other structures such as eccentrics have been employed in place of cranks, and hence an eccentric shaft with the eccentrics suitably 40 dephased may be employed in place of the crank shaft shown, but as such structures are well known expedients and considered as equivalents of crank shafts it is not deemed necessary to illustrate them, since 45 the principles of the invention are not dependent upon any specific mechanical structures.

What is claimed is:—

- 50 1. In an explosion engine, a power cylinder provided with inlet and exhaust ports, two coacting reciprocating pistons therein with one having a range of movement to cover and uncover the inlet and exhaust ports, a driven member, and connections between the pistons and driven member constructed and related to cause the pistons to move in the same direction and in opposite directions during different phases of the operation of the engine.
- 55 60 2. A two cycle explosion engine provided with a cylinder having inlet and outlet ports constituting the sole inlet and outlet ports of the explosion chamber of the engine, a power piston having a range of movement 65 to cover and uncover said ports, another

power piston within the cylinder movable toward and from the first-named piston, a driven member, constantly active driving connections between the second-named piston and the driven member, and other constantly active driving connections between the first-named piston and the driven member, said second-named piston being confined in its range of movement to that portion of the cylinder between the ports and 70 the driven member.

3. An explosion engine of the two cycle type provided with a power cylinder having inlet and outlet ports constituting the sole inlet and outlet ports of the explosion chamber of the engine, a driven member, a piston mounted in the cylinder and connected to the driven member and having a range of movement to cover and uncover said inlet and outlet ports, said piston and cylinder 80 being also constructed to operate as a pump for compressing air for introduction into the cylinder on the explosion chamber side of the piston, and another piston mounted in the cylinder and connected to the driven member and related to the first-named piston to provide an explosion chamber between the two pistons, said last-named piston having its entire range of movement 85 confined to a portion of the cylinder spaced 90 from said ports.

4. An explosion engine of the two cycle type provided with a power cylinder having inlet and outlet ports constituting the sole inlet and outlet ports of the explosion cylinder of the engine, a driven member, a piston mounted in the cylinder and connected to the driven member and having a range of movement to cover and uncover said inlet and outlet ports, said piston and cylinder 100 being also constructed to operate as a pump for compressing air for introduction into the cylinder on the explosion chamber side of the piston, and another piston mounted in and confined in its travel to a portion of 110 the cylinder spaced from said ports and connected to the driven member and related to the first-named piston to provide an explosion chamber between the two pistons, the first-named piston being provided with a deflector in position to direct fluid under pressure entering the cylinder through the inlet port toward the other piston.

5. An explosion engine of the two cycle type comprising an axially elongated cylinder closed at one end and provided with inlet and exhaust ports adjacent to said closed end and also with an outlet communicating with the inlet port of the cylinder, said inlet and exhaust ports constituting the sole ports 120 of the explosion chamber of the engine, a piston within the cylinder in position to move toward and from the closed end of the cylinder to form a pump and having a range 125 of movement to cover and uncover said inlet 130 and exhaust ports.

- and exhaust ports, and another piston in the cylinder movable toward and from the first-named piston and confined in movement to that portion of the cylinder remote from the closed end and spaced from the said inlet and exhaust ports of the explosion chamber, the engine being also provided with a driven member and connections therefrom to both pistons.
6. An explosion engine of the two cycle type provided with a power cylinder having inlet and outlet ports, a driven member, a piston mounted in the cylinder and connected to the driven member and having a range of movement to cover and uncover the inlet and outlet ports, said piston and cylinder being also constructed to operate as a pump for compressing air for introduction into the cylinder on the explosion chamber side of the piston, and another piston mounted in the cylinder and connected to the driven member and related to the first-named piston to provide an explosion chamber between the two pistons, the first-named piston being provided with a deflector in position to direct fluid under pressure entering the cylinder through the inlet port toward the other piston, the engine being also provided with a crank shaft having cranks in substantially ninety degree relation with one crank shorter than the other, with the shorter crank connected to the first-named piston and the longer crank to the second-named piston, both pistons being hollowed out at the contiguous ends.
7. An explosion engine of the two cycle type provided with a power cylinder having inlet and outlet ports, a driven member, a piston mounted in the cylinder and connected to the driven member and having a range of movement to cover and uncover the inlet and outlet ports, said piston and cylinder being also constructed to operate as a pump for compressing air for introduction into the cylinder on the explosion chamber side of the piston, and another piston mounted in the cylinder and connected to the driven member and related to the first-named piston to provide an explosion chamber between the two pistons, the first-named piston being provided with a deflector in position to direct fluid under pressure entering the cylinder through the inlet port toward the other piston, the engine being also provided with a crank shaft having cranks in substantially ninety degree relation with one crank shorter than the other, and the respective cranks connected to respective pistons.
8. An explosion engine of the two cycle type provided with a power cylinder having inlet and outlet ports, a driven member, a piston mounted in the cylinder and connected to the driven member and having a range of movement to cover and uncover the inlet and outlet ports, said piston and cylinder being also constructed to operate as a pump for compressing air for introduction into the cylinder on the explosion chamber side of the piston, and another piston mounted in the cylinder and connected to the driven member and related to the first-named piston to provide an explosion chamber between the two pistons, the first-named piston being provided with a deflector in position to direct fluid under pressure entering the cylinder through the inlet port toward the other piston, the engine being also provided with a crank shaft having cranks in substantially ninety degree relation with one crank shorter than the other, with the shorter crank connected to the first-named piston and the longer crank to the second-named piston.
9. In an explosion engine, a power cylinder having inlet and exhaust ports intermediate of its length, pistons within the cylinder movable on opposite sides of the ports with one of the pistons having a range of movement with respect to the ports to close and uncover them, a driven member, and connections between the pistons and driven member constructed to cause movements of the pistons in the same direction and in opposite directions for like periods of time and to different extents during different phases of the operation of the engines.
10. An explosive engine provided with a power cylinder having inlet and exhaust ports, and two coacting pistons forming an explosion chamber between them, said pistons having different lengths of stroke and having connections for causing their movements to be in substantially ninety degree relation, one of the pistons having a range of movement to cover and uncover the inlet and exhaust ports.
11. In an explosion engine, a power cylinder having inlet and exhaust ports between its ends, coacting pistons reciprocable within the cylinder with one of the pistons having a range of movement to wholly cover and uncover the said ports, said pistons having connections constructed and related to cause the pistons to move in the same direction and to move in opposite directions during different times in the cycle of operation of the engine.
12. In an explosion engine, a power cylinder having intermediate intake and exhaust ports, a pair of pistons within the cylinder reciprocable on opposite sides of the ports and one piston having a range of movement to cover and uncover the ports, and means for causing movements of the pistons in the same direction and in opposite directions for like periods of time during different phases of the cycle of operations.
13. In an explosion engine, a power cylinder having intermediate intake and exhaust ports, a pair of pistons within the cylinder reciprocable on opposite sides of the ports and one piston having a range of movement to cover and uncover the ports, and means for causing movements of the pistons in the same direction and in opposite directions for like periods of time during different phases of the cycle of operations.

- der having intermediate intake and exhaust ports, a pair of pistons within the cylinder, reciprocable on opposite sides of the ports and one piston having a range of movement 5 to cover and uncover the ports, and means for causing movements of the pistons in the same direction and in opposite directions during different periods of the cycle of operations, the cylinder and one of the pistons 10 being related to cause a compression of the charge directed to the inlet port.
14. In an explosion engine, a power cylinder provided with inlet and exhaust ports intermediate thereof, a pair of pistons 15 within the cylinder having the adjacent heads hollowed out to form part of an explosion chamber between the pistons, one piston and one end of the cylinder being related to serve as a pump and said end of the 20 cylinder being connected to the inlet port of the cylinder, a crank shaft having cranks relatively displaced by approximately ninety degrees, and connections between the cranks and respective pistons to cause movements of the pistons in accordance with the 25 displacement of the cranks.

15. In an explosion engine, a power cylinder provided with inlet and exhaust ports intermediate thereof, a pair of pistons within the cylinder having the adjacent heads hollowed out to form part of an explosion chamber between the pistons, one piston and one end of the cylinder being related to serve as a pump and said end of the cylinder being connected to the inlet port of the cylinder, a crank shaft having cranks relatively displaced by approximately ninety degrees, and connections between the cranks and respective pistons to cause movements of the pistons in accordance with the displacement of the cranks, the crank connected to one piston being shorter than that connected to the other piston to cause a corresponding difference in travel of the pistons. 30
